ROD BENDER

William Vernon Bernard, El Cerrito, Calif.

Application April 8, 1938, Serial No. 200,921

9 Claims. (Cl. 81—15)

This invention, a rod bender, is specifically designed for bending the ends of tie rods about the studs or purlins of concrete forms, and due to its specific structure and method of operation converts the tie rod into a combined tying and spacing element.

Different methods are used for tying and spacing the walls of concrete forms, the most commonly used being in the form of wires which are looped about the studs and through the form and twisted for tightening, with a strut placed between the walls as a spacing element.

Other systems employ special tie rods, which in some cases form both, a tying element and spacing element, however such devices as are now used are uneconomical, due to the cost of forming shoulders, clips, and other devices and means necessary for their proper functioning.

This invention utilizes plain circular or non-circular rods which are merely cut to length, and formed with or without notches according to whether the projecting ends of the rods are to be broken off after the concrete has set, or are to be retained to function as facing anchors.

The rods used may have one of their ends preformed or both ends may be formed on the job, as desired, since the tool comprising the invention is adapted for forming both, right hand and left hand bends at will and without change or adjustment.

In the accompanying drawing similar reference characters are used to designate similar parts throughout the several views, of which:

Fig. 1 is a plan view of the invention shown in the position where the rod bending operation has just been completed.

Fig. 2 is a side view of the clamp handles of Fig. 1.

Fig. 3 is a front elevation of the invention showing one handle in position of completing a bend.

Fig. 4 is a fragmentary plan view illustrating one of the forming arms in open position ready to receive the rod to be bent, and

Fig. 5 shows the rod bent about a stud and anchored thereto to form the spacing element.

The anvil 10 coincidentally functions as a pivot block and lower clamp jaw, and has straddling ears 11 and 12 projecting rearwardly and continuing into an upper clamp-handle 13 projecting rearwardly therefrom. The anvil also has integral lateral ears 14 and 15 formed at its opposite ends for mounting of the forming arms. The anvil 10 also has a rod aligning and retaining groove or slot 16 formed in its top face and

throughout its width, to receive and transversely position the tie rod 17 for bending, the terminal ends of the front wall of the groove forming fulcrums for bending the rod.

A lower clamp-handle 18 for the upper clamp jaw has an eye 19 which fits between the ears 11 and 12 and is pivoted therebetween by means of a pivot 20 and has an integral upper clamp jaw 21 provided with an undergroove 22 formed complementary to and in registrable relation, to the groove 16 in the anvil 10, so that, by manually urging the two clamp handles 13 and 18 toward each other, the rod 17 can be fixedly held between the jaws within the grooves during the bending operation.

The operating levers 23 and 24 are respectively mounted at each end of the anvil 10 and pivoted by means of pivots 25 to the respective ears 14 and 15, the axis of the pivots 25 falling in the plane of the rear wall of the groove 16. Each operating lever 23, 24, has a forming arm 26 integral therewith and formed substantially at right angles thereto.

Each forming arm 26 is provided with a rod-receiving recess 27 axially aligning with the rod-retaining groove 16 when the levers 23 and 24 are in one position and herein termed the open position, for endwise reception of the rod, and this recess has only a bottom wall and a back wall, the front wall being omitted so as to avoid the introduction of any obstruction against removal of the tool from the bent rod.

A stop, or rod-locating gauge 28 is formed adjacent the outer end of each forming arm respectively for right hand and left hand bends, and forms an obstruction for cooperation with the end of the rod as the rod is threaded through the grooves 27, 16 and 27, the stop on only one of the arms functioning as a gauge, depending on the direction of insertion of the rod, the stops projecting forwardly into the recesses 27.

When a rod 17 is threaded through the axially aligned recesses 27, 16 and 27 with the tool in open position as illustrated fragmentarily in Fig. 4, the forward end of the rod will strike the gauge 28 and be stopped thereby, thus establishing the bend points on the rod relative to its terminal end, consequently establishing the spacing between the walls 29 of the forms.

Each forming arm 26 has an integral lug 30 overhanging the portion of the recess 27 between the axis of the pivot 25 and the end of the anvil 10 when the tool is open, forming a short length of top wall for the recess 27 and which swings out of the way in non-obstructionless relation to 55

the rod as the tool is moved to closed position, whereby, when the tool is open as in Fig. 4, the rod can only be inserted into or removed from the tool endwise or longitudinally, but when the tool is closed about the bent rod as illustrated in Fig. 1, the overhanging lug 30 has moved to a position in which it clears the rod and permits removal of the tool from the bent rod merely by releasing the clamp 21 and lowering the tool.

10 This overhanging lug 30 functions to hold the tool on the rod when the rod is straight without assistance on the part of the clamp 21, thus facilitating operation of the tool.

As will be noted in Fig. 1, the front face of the lug 30 is in alignment with the rear wall of the groove 16, thus offering no further holding or obstructive effect toward removal of the tool from the bent rod 17, the tool being retained on the bent rod only by means of the clamp jaw 21 through the effort applied through the handles 13 and 18, which, when released, will release the tool from the rod.

It will be noted that the front wall of the groove 16 prevents frontal removal of the rod, and this front wall therefore cooperates with the lugs 30 which prevent perpendicular removal of the straight rod while permitting perpendicular removal of the bent rod.

The operation of the invention is as follows; 30 The other end of the rod 17 (not shown), is pre-formed to the form shown in Fig. 1, and the rod is inserted through the form, and which rod will extend as indicated by the dotted line 31. The tool, with all handles gathered or clustered, indicated by the dotted position, is threaded onto the end of the rod, easily sliding back until the extreme end 32 of the rod abuts against the gauge or stop 28, after which arm 23 is urged in the direction of the pointer 33 while the clamp arms 13 and 18 are gripped to clamp the rod and then urged in the direction of the pointer 34, forming the first bend 35 about the stud 36.

45 Arm 23 is then released, and while still gripping arms 13 and 18, arm 24 is urged in the direction of the pointer 37 forming the second bend 38. The clamp levers 13 and 18 are then released and the tool removed by lowering the tool slightly and withdrawing the tool from the bent rod, the retaining lugs 30 in the final forming, or closed position of the levers readily clearing the bent rod and permitting direct removal of the tool from the rod.

50 A staple or nail 39 is then driven into the stud and bent over the rod as shown, thus spacing the walls of the form accurately, since the rods are cut to exact lengths and each end is bent about the stud and spiked as shown in Fig. 5.

This tool is thoroughly practical for use under ordinary conditions with the clamping arrangement 18, 19, 21, 13, omitted, under which conditions only the two handles 23 and 24 are used, handle or arm 24 being forced clear around from its initial position to the position shown in Fig. 1 to form both bends.

65 The tool therefore, is constructed in both forms, with, and without, the clamping arrangement, the clamping arrangement obviously having its advantages, though it does increase the cost of manufacture of the tool.

70 If the rod is to be broken off after the concrete has set, one or more weakening notches 40 are provided, which permits their being broken off by a series of reverse flexures.

75 It will be understood that variations in construction and arrangement of parts, which vari-

ations are consistent with the appended claims, may be resorted to, without detracting from the spirit or scope of the invention, or sacrificing any of the advantages thereof.

I claim:

1. A rod bender comprising; an anvil having a rod-retaining groove having a front wall and formed in the upper face of the anvil; a bending arm pivotally attached to each end of said anvil and comprising an operating lever and integral 10 forming arm formed substantially at right angles to the lever; each forming arm having a rod-receiving recess formed therein, and a retaining lug overhanging a portion of the recess adjacent to the anvil for retaining the rod bender on the 15 rod when the rod is straight and the rod bender is open, and clearing the rod and permitting direct removal of the rod bender from the rod when the rod is completely formed to its final shape and the rod bender is in its closed position. 20

2. A structure as defined in claim 1, in which gauging means is provided at the outer terminal end of each forming arm for selective use for gauging the end of a rod as related to said anvil, 25 through cooperation with the end of the rod as the rod bender is threaded onto the rod.

3. A structure as defined in claim 1; a first handle integral with said anvil and extending rearwardly therefrom; a clamp having a second 30 handle cooperatively related to said first handle and pivotally connected to said anvil with the clamp cooperatively related to said rod receiving groove for clamping a rod in the groove in said anvil. 35

4. A rod bending tool comprising; an anvil having a rod retaining groove extending throughout its width, the ends of the front wall of said groove functioning as fulcrum points for bending the rod; a bending arm pivotally attached to each end of said anvil and having an integral forming arm provided with a rod-receiving recess and a lug overhanging the portion of said recess adjacent to said anvil for retaining the rod in said groove while the rod is straight and during 45 the bending operation, and clearing said rod after bending is completed and the tool is closed to permit direct removal of said tool from said rod.

5. A tool as defined in claim 4; and clamping 50 means operable at will and associated with said anvil for clamping said rod in predetermined position in said rod-retaining groove, and additionally functioning as a lever arm for bending 55 said rod.

6. A rod bending tool comprising; an anvil having a rod-retaining groove having a front wall and formed in the top of the anvil adjacent the front edge thereof and extending throughout the 60 width thereof; the ends of said front wall functioning as fulcrum points for bending a rod; an operating lever pivotally mounted on each end of said anvil; a forming arm integral with and formed substantially at right angles to each 65 operating lever and having a rod-receiving recess aligning with said rod-retaining groove when said levers are in one position for endwise reception of the rod; and a rod-retaining lug integral with each lever and overhanging the portion of the recess between the end of the anvil and the axis of the pivot of the operating lever for cooperation with the rod when said levers are in said one position, and clearing the rod when said levers are in another position with the rod com- 70 75

pletely formed, to permit direct removal of the tool from the formed rod.

7. A tool as defined in claim 6; a clamp member having an under-groove aligning with said rod-retaining groove and superposedly related to said anvil; and cooperative handles integral respectively with said anvil and with said clamp member and pivotally connected together for manual urging to clamp the rod within and between the groove and recess.

8. A tool as defined in claim 6; and gauging means associated with one of said forming arms and obstructively related to the outer end of

said rod-receiving recess forming a stop for the end of the rod for gauging the position of the end of the rod relative to said fulcrum points as the straight rod is threaded through the open tool for determining the position of the bends.

9. A tool as defined in claim 4; and a stop lug formed at the outer end of each forming arm and projecting into the rod-receiving recess; the lugs on the respective arms functioning selectively as a gauge or stop for the end of the rod when the tool is threaded onto the rod for right hand or left hand bending of the rod.
